UNITED STATES PATENT OFFICE.

EDMOND PHILÉMON BEAUDET, OF MONTREAL, QUEBEC, CANADA, ASSIGNOR TO
ALEXANDER WINK GRANT, OF MONTREAL, QUEBEC, CANADA.

MOP-FRAME.

1,344,936.

Specification of Letters Patent. Patented June 29, 1920.

Application filed September 16, 1919. Serial No. 324,229.

To all whom it may concern:

Be it known that I, EDMOND PHILÉMON BEAUDET, a subject of the King of Great Britain, and resident of the city of Montreal, Province of Quebec, Canada, have invented certain new and useful Improvements in Mop-Frames, and do hereby declare the following to be a full, clear, and exact description of same.

10 This invention relates to a frame adapted to have a mop fabric attached thereto and to be manipulated preferably through the medium of a long handle for the washing and dusting or general cleaning of floors, 15 walls, windows and the like. The invention appertains particularly to a frame comprising pivoted sections held by a latch device in a position maintaining the fabric in a substantially flat, stretched-out position, 20 such latch device being operative to release the frame and permit of the folding or collapsing of same to loosen the fabric so that it may be thoroughly shaken or squeezed out to remove foreign matter therefrom.

An object of the present invention is to facilitate the manufacture of mop frames of the above specified type and to economize in such manufacture by the employment 30 of simply constructed members adapted to be readily assembled in a coöperative arrangement devised to reduce the number of parts heretofore used and to promote a more complete folding of the frame sections.

The above with further objects and advantages will be hereinafter more fully described and particularly pointed out in the accompanying claims.

40 For full comprehension, however, of my invention reference should be had to the accompanying drawings forming a part of this specification, in which similar reference characters indicate the same parts and 45 wherein:

Figure 1 is a plan view of my improved mop frame;

Fig. 2 is a side elevation of the frame in folded position; and

50 Fig. 3 is a transverse section on line 2—2 Fig. 1.

Fig. 4 being an enlarged detail side elevation partly in section and partly broken

away, to illustrate the engagement of the latch plate with the frame.

As shown in the drawings my improved frame includes sections 2 and 3 bent into U-form and overlapped at their open inner ends where they are pivotally connected to swing toward each other through the medium of a wire bail 4, the lower ends of which pass inwardly through registering openings in the overlapping ends of the sections. The pivotal sections are preferably made from strips of metal plate and present openings 5 in the opposite sides thereof near their outer ends for the reception of removable pins 6 by means of which a mop fabric 7 is attached to the frame. The fabric is located beneath the frame and has its ends carried upwardly and inwardly over the frame ends, the pins 6 being threaded through the fabric and holding same in position with the frame ends which are rounded at 3^a bearing 75 thereon.

The frame sections are held in extended position as shown in Fig. 1 by a latch 8 which is located between the frame members at their pivoted ends, being fulcrumed between its ends by depending apertured lugs 9 mounted upon a bar 10 extending transversely of the frame and bearing at its opposite ends in the sides of the frame section 3 near the upper edges thereof and 80 adjacent the pivotal connection of the sections. In the preferred construction the latch is of plate form and extends in a flat position, substantially from side to side of the frame, one end of the latch presenting integral lugs or fingers 11 which extend laterally from the latch over the sides of the frame section 2 and are adapted to engage shoulders A thereon which are most suitably presented by forming notches 90 12 in the upper edges of said frame section. This engagement of the latch with the section 2 and the connection of the latch with section 3 through the bar 10, establishes a rigid connection between the 95 two sections and prevents the swinging of same toward each other while the direct engagement of said latch with section 2 eliminates intermediate parts. The end 13 of the latch is upwardly offset above the normal plane of the main portion of the latch 100 105

to form a convenient presser portion whereon pressure can be applied and the latch rocked on its fulcrum to disengage the fingers from the frame.

- 5 A coiled spring 14 encircling one end of the bail 4 where it extends inwardly beneath the latch forms the sides of the frame sections, has one end 15 thereof engaged with one side of section 2 and its opposite end 10 16 bearing upon the underside of the presser end 13 of the latch thereby tending to yieldingly maintain the latch fingers 11 in engagement with frame section 2.

When it is desired to collapse the frame 15 to loosen the mop fabric so that it can be squeezed out or renewed, the presser end of the latch is depressed thus permitting the sections 2 and 3 to be swung inwardly toward each other. This swinging movement 20 of the section is yieldingly resisted and sudden collapsing of the frame prevented by said spring 14 which in addition to influencing the latch also provides a connection between the two frame sections when the 25 latch is disengaged from section 2, such connection being set up through the engagement of the end 15 with section 2 and the engagement of end 16 with the latch and through the latter, with section 3. In order, however, 30 to permit of the sections being swung to a position with their free ends in close proximity to each other so that the ends of the mop fabric are brought close together and the fabric thereby so folded as to be 35 conveniently inserted in a wringer for practically its whole length, I have made section 3 of less width than section 2 and disposed the pivoted ends of the former within those of section 2 thus permitting an intimate folding of the sections as shown in 40 Fig. 2, wherein section 2 straddles section 3 for the major portion of its length.

The frame is firmly braced at the center by a bridge-piece which is formed to firmly 45 support and brace the different members without interfering with the described movements thereof. Said bridge-piece consists of a flat metallic strip 17 extending between the sides of section 3 beneath the inturned 50 ends of bail 4 and having its ends extended upwardly at 18 inside the pivoted ends of the frame sections to the top edge thereof, then continued outwardly over such pivoted ends and downwardly as at 19 on the outer 55 side of the latter, thus forming downwardly facing hooks straddling the ends of the sections. The upwardly and downwardly extending ends of the bridge-piece are suitably apertured for the passage of the inwardly extending ends of the bail 4 there- 60 through, said bail ends being thus provided with bearings at these points while apertured lugs 20 struck up from the strip 17 provide bearings for the extreme inner ends 65 of the bail.

The bridge-piece is rigidly fixed to section 3 by the bar 10 which passes through notches 21 in the upwardly extending portions 18 and prevent relative movement between the bridge-piece and said section, the collapsing 70 of the frame being, in this construction, accomplished by the swinging of section 2 which has its pivoted ends rounded at 2^a to provide ample clearance between them and the overhanging portions of the hooked ends 75 of the bridge-piece.

The above described bridge-piece provides a firm bracing bond between the sections at their pivoted ends, without interfering with the movements of the different members. The latch has an unobstructed movement between the hooked-ends of the bridge-piece and the downwardly facing position of the latter where they span the sections at their pivotal point eliminates the necessity for cross-pieces at the sides of such pivot point and thus enables the sections to be constructed so that the space between the bottom edge of each side of the under section 2 and the bottom edge of each side of the 85 narrower section 3 overlapped thereby, is left unobstructed from the free ends of the sections to the closed ends thereof. This construction permits the above described intimate folding to be accomplished. 95

In the preferred construction the strip 17 is located below the level of the lower edges of the pivoted ends of sections 2 and 3 to provide a flat surface extending from side to side of the frame at the center thereof and below the level of the central portion of the frame for the purpose of providing a firm bearing upon the fabric at this point and to elevate the frame at the center to promote the accumulation of dirt and like foreign 105 matter at the center of the fabric mop and prevent similar accumulation at the sides thereof where it would be continually spread over the surface being mopped.

A hook 22 pivotally carried by the frame 110 section 2 is adapted to swing over and engage the bail 4 carrying the handle and thus hold same securely to the frame. With this arrangement one end of the frame may rest upon the floor and the cloth, being in 115 stretched out position will dry quickly.

A mop frame constructed as above described can be economically manufactured, the majority of the members being stamped out from sheet metal and readily formed, 120 the simplicity of their construction and particular arrangement promoting a quick assembly requiring a minimum number of parts.

What I claim is as follows:

1. A mop frame, including sections pivoted together to swing toward each other, one of said sections having notches formed therein and a presser latch carried by the other section and fulcrumed at opposite 130

points adjacent the sides of the frame to swing with relation thereto, said latch having integral fingers adapted to engage within said notches and prevent the swinging 5 of the frame sections toward each other.

2. In a mop frame, a bail the end portions of which form transverse pivot bars; two U-shaped frame sections pivoted at their open ends upon said pivot bars and adapted to 10 swing toward each other, the upper edges of one of such sections presenting latch-engaging shoulders adjacent its pivoted ends, and a latch in the form of a single plate extending transversely of the frame 15 and being pivoted to one frame section and presenting lugs to engage the shoulders in the upper edges of the other section.

3. A mop frame, including sections of U-form pivoted at their free ends to swing 20 toward each other, a latch carried by one of said sections and adapted to engage the other section to prevent the swinging of the sections and a bridge-piece extending between the pivoted ends of the sections and 25 presenting hooked ends straddling the upper edges of said sections at their pivoted ends.

4. A mop frame, including sections of U-form with overlapped ends having registering 30 openings therein, a bridge-piece extending between said overlapped ends near the lower edges thereof, the ends of the bridge-piece extending upwardly inside the overlapped ends, continuing outwardly over 35 same and downwardly outside such ends and the upward and downward extensions of the bridge-piece being formed with openings registering with the openings of the

overlapped ends, a bail, the ends of which pass inwardly through said registering 40 openings and pivotally connect the overlapped sections and a latch carried by one of the sections and adapted to engage the other section.

5. A mop frame, including sections of U- 45 form with overlapping ends having registering openings therein, a bridge-piece extending between said overlapped ends near the lower edges thereof, the ends of the bridge-piece extending upwardly inside the 50 overlapped ends, continuing outwardly over same and downwardly outside such ends and the upward and downward extensions of the bridge-piece being formed with openings registering with the openings of the overlapped ends, apertured lugs struck up from the bridge-piece between the ends thereof, 55 a bail, the ends of which pass inwardly through said registering openings to pivotally connect the overlapped sections and bear 60 in said apertured lugs, a bar mounted at its ends in the opposite sides of one of said sections adjacent the pivotal connection, a latch fulcrumed upon said bar extending in flat position between the sides thereof, 65 such latch having a presser end and an end adapted to engage the other of said sections and a spring encircling said bail, one end of the spring engaging with the last mentioned section and the opposite end bearing 70 upon the underside of the presser end of the latch.

In testimony whereof I have signed my name to this specification.

EDMOND PHILEMON BEAUDET.
